UNITED STATES PATENT OFFICE.

RUSSELL A. TRACE, OF DAYTON, OHIO, ASSIGNOR TO BUCKEYE IRON AND BRASS WORKS, OF DAYTON, OHIO, A CORPORATION OF OHIO.

CAKE-FORMING MACHINE.

Application filed October 18, 1920. Serial No. 417,824.

To all whom it may concern:

Be it known that I, RUSSELL A. TRACE, a citizen of the United States, residing at Dayton, in the county of Montgomery and State of Ohio, have invented certain new and useful Improvements in Cake-Forming Machines, of which the following is a specification, reference being had therein to the accompanying drawing.

10. My invention relates to machines for forming cakes and in particular for forming cakes from oil bearing material.

This material is delivered to the former customarily from a cooker and after it is 15 formed it is delivered to a press where the oil is pressed from the material.

In a machine of this type using low and high pressure oil, it is highly desirable to utilize low pressure for the initial forming 20 operation and high pressure for the final forming operation.

It is also desirable to utilize as little of the high pressure as possible in order to economize on the amount of fluid which 25 must be employed. The high pressure is customarily kept at about 4,000 pounds, while the low pressure is in the neighborhood of 400 to 500 pounds at its maximum.

30. My invention accomplishes the object of utilizing the low pressure up to the very last stage of the operation of the former and then the high pressure is applied so that only a very small quantity of oil or other liquid used in the former is needed 35 to give this final finishing step to the operation.

It is desirable also that the transformation from low pressure to high pressure 40 should take place automatically without the attention of the operator through any gauge or similar mechanism and that it should be entirely automatic so that it should not depend upon the human element at all for the efficient and uniform operation of the former.

Referring to the drawings:

Figure 1, is a side elevation on the side containing the valves and feed lines from the low and high pressure accumulators.

50. Fig. 2, is a side elevation of the other side of the former showing the mechanism of the carriage;

Fig. 3, is a top plan view of the former

showing a portion of it broken away to disclose the valves connected with the ram and showing in dotted lines the ram and the cylinder in which the ram travels;

55. Fig. 4, is a detail view of a section on the vertical or main axis of the control valve casing and the valves therein disclosing the low pressure check valve and the high pressure inlet valve;

Fig. 5, is a section of the exhaust valve;

Fig. 6, is a section of the low pressure 60 inlet valve;

Fig. 7, is a top and bottom plan view of a portion of the high pressure inlet valve; and enlarged side elevation, and,

Fig. 8, is a section of the supporting base 70 cylinder and ram traveling therein upon which the movable forming head is mounted.

Referring to the drawings, 1, is a base 75 upon which is mounted the cylinder 2. The cylinder 2 is divided into two members, a cup-shaped member 3 and a cylindrical member 4. 4 is the guide for the ram 5, while 3 does not come in contact with the ram 5, but is separated from it by a space 80 as at 6. This space communicates with the outside through a vent 7 to permit the free passage of air and the circulation therein for the evaporation of any leakage or moisture which may get by the packing 8. 9 is 85 a cylindrical passage way communicating with the interior 10 of the ram. This passage way is cushioned by the plug 11 when the ram is in its lowermost position. This cylindrical passage way communicates at 90 12 with the inlet pipe 13 and the outlet pipe 14 which communicates with the outlet valve 15, shown in detail in Figure 5. 16 is the low pressure inlet line and 17 is the low pressure inlet valve. This valve is operated 95 through the plunger 18 by the lever 19 which also operates the exhaust valve 15 through the pin 20. This lever is operated up and down; when it is moved upwardly it opens the inlet valves and when it is moved downwardly the spring in the inlet valve closes it and it opens the outlet or exhaust valve 15. 21 is a check valve in the inlet low pressure line 22. 23 is the control valve casing, 24 is the high pressure inlet 100 passage way, 25 is a movable presser head while 26 is the stationary head supported by the columns 27. 28 is a charging hopper

into which a predetermined quantity of meal is dumped from the cooker. The meal is delivered from this hopper into the movable forming head at 29. This hopper is operated by a rod 30. This rod carries a piston 31 in the cylinder 32. The piston is moved in the left hand direction when pressure is applied to the supply line 33 and is moved in the right hand direction when pressure is supplied through the pressure line 34. The precise valve arrangement at 35 which is controlled by the operating lever 36 may be of any desired character.

37 is a supporting frame upon which the hopper mechanism travels.

Referring in detail to Figure 4, there will be seen the control valve casing 23. With this casing there communicates the inlet low pressure passage way 22 at 38. The inlet pressure passes through 39, past the check valve 40 which is held open by the low pressure inlet. The low pressure proceeds through the main passage way 41, through 13 to the ram. The low pressure also passes through the passage way 42, to the area 43, behind the head 44 carried by the stem 45 of the high pressure inlet valve designated as 46. This valve is normally kept in seated position by the spring 47, held in a plug 48, screwed into the casing 23. The high pressure line 24 communicates with the high pressure inlet port in the casing 23 at 49. When the valve 46 is opened this passage way 24, 49, and the passage way 50 are in communication, allowing the passage of high pressure fluid through the line 13 to the press for the final operation.

Referring to Figure 5, it will be seen that the stem 20 carries a valve member 51. This member is normally seated by the spring 52 and actuated by the pin 53.

In Figure 6 will be seen the inlet valve where a similar construction is employed. 18 is the pin actuating the valve member 54 held in position by the spring 55, which is actuated by the pin 56.

By the use of the word passage or passageway above, is understood the element provided with such passage or passageway rather than the passage itself.

Method of operation.

The operator stands in front of the machine between the handles 19 and 36.

When he lifts the handle 19, after having charged the head 25 with the hopper 28, he thereby opens up the valve 17 communicating with the low pressure line 16. This admits low pressure fluid starting at 150 pounds pressure through 38, 39, lifting 40, passing by 41 to 13 and thence to the ram. This moves the movable head towards the stationary head.

As soon as the pressure in the line, due to the increasing pressure, rises to about

450 to 500 pounds, the back pressure through 42 in the chamber 43 acting upon the head 44, actuates the stem 45 and the valve 46, depressing the spring 47, allowing the high pressure to pass into the line 50 and into 70 13. It also backs up through 41, closes the check valve 40 cutting off the low pressure supply line, passes through 42 and reinforces the pressure in 43. The forming operation is almost complete when this 75 takes place so that very little liquid is used and very little of the pressure is consumed, making the system quite economical.

The operator then, upon finishing the forming operation, depresses the lever 19, 80 thereby allowing the inlet valve to close, that line being checked by the check valve 21, and pushing the pin 20 down against the pressure of the spring 55 in the outlet valve 15, allowing the liquid to escape from 85 the ram.

The operation may be repeated as often as desired.

The pressure is balanced to an extent by permitting the oil to circulate around 58 90 from 57. The back pressure must overcome only the area of the valve member 46 when seated.

It will be noted that the standards 27 95 supporting the stationary head 26 are located behind the movable forming or presser head and to either side of the machine. The purpose of this is to allow the charging and the adjustment of the cloth without interference on the part of the operator. It 100 is a matter of considerable advantage to be able to make these adjustments and to superintend the charging on the part of the operator without having standards in the operator's way around which he must work in 105 adjusting the cloth and fixing the charge ready for forming.

The timing of this operation of forming is carefully worked out in connection with the remainder of the procedure of cooking and pressing so that any undue delay at this stage of the proceeding, which is frequently the case in prior machines of this character, is a matter of handicap. My invention obviates any cause for delay and provides a 110 machine to which free access may be had.

While I have shown and described certain features as constituting my invention, it will be understood that parts have been shown for purposes of illustration only, and that I do not desire to be limited to such details, as obvious modifications will occur to a person skilled in the art.

Having thus fully described my invention, what I claim as new and desire to secure by Letters Patent, is:—

1. In a former, a low pressure inlet valve, an outlet valve, means for successively actuating said valves at will, a high pressure inlet valve, means for cutting off a low pres- 130

sure supply at a predetermined pressure, and means for applying a high pressure to the forming head after the low pressure has been applied.

5. 2. In a former, a low pressure inlet valve, a high pressure inlet valve, an outlet valve, means for operating said low pressure inlet valve and outlet valve at will, means for operating said high pressure valve automatically at a predetermined pressure, and cutting off the low pressure through the low pressure valve whereby low pressure and high pressure are successively applied. 70

10. 3. In a former, a low pressure supply line, a high pressure supply line, a low pressure inlet valve, a high pressure inlet valve, an outlet valve, means for operating said low pressure inlet and outlet valves, an inlet check valve adapted to be opened by the low pressure and closed by the high pressure and means for opening the high pressure valve when the low pressure reaches a predetermined pressure, a ram, means for communicating pressure to said ram, and a check valve in the low pressure supply line, whereby low pressure and high pressure are successively applied to said ram. 75

15. 4. In a former, a low pressure supply, a low pressure supply line connected to a low pressure inlet valve, a low pressure inlet valve, a low pressure line from said inlet valve to a control valve, a check valve in said line last mentioned, a control valve having a passage way communicating with the ram, a check valve adapted to be opened by said low pressure, and seated by high pressure, a high pressure supply line, a high pressure inlet valve located in said control valve casing, a high pressure passage way communicating with the low pressure passage way, a passage way communicating with the low pressure passage way and one end of the high pressure inlet valve to admit low pressure to shift said high pressure inlet valve when the low pressure reaches a predetermined point, a ram, and an outlet line and outlet valve connected to said ram, whereby low pressure and high pressure are successively applied to said ram. 100

20. 5. In a control valve, a casing, a low pressure inlet, a low pressure passage way, a check valve, a high pressure passage way in communication with said low passage way, an exit passage way, a high pressure valve consisting of a stem and a valve member, a piston on the stem of said high pressure valve, a cylinder in which said piston travels and means for communication between said low pressure passage way and said cylinder, a high pressure passage way communicating with a cylinder in which said valve member travels, a tapered shoulder on said valve member and a plurality of longitudinal passage ways on the exterior thereof, a guiding casing for said valve member located in 105

said cylinder having a plurality of ports communicating with said high pressure passage way and said longitudinal passage ways on said high pressure valve member, resilient means to maintain said high pressure valve member normally seated, whereby when the back pressure in the low pressure line moves the piston of the high pressure valve and unseats said valve member, the high pressure will be admitted past the high pressure valve member, the check valve will be seated and high pressure will pass out the existing passage way. 110

6. In a former, a base, a cylinder mounted thereon, a ram working in said cylinder, said ram having a cylindrical area therein, a tubular passage way through said support in sliding engagement with said ram and in communication with the interior thereof, means for preventing leakage between said tubular passage way and said ram; a said cylinder in which said ram travels having a communicating vent, a movable forming head carried by said ram, a stationary forming head, and means for successively applying low pressure and high pressure to said ram and forming heads. 115

7. In a former, a base, a cylinder mounted thereon, a ram working in said cylinder, said ram having a cylindrical area therein, a tubular passage way through said support in sliding engagement with said ram and in communication with the interior thereof, means for preventing leakage between said tubular passage way and said ram; a vent communicating with said cylinder in which said ram travels, a movable forming head carried by said ram, a stationary forming head, a low pressure supply line, a high pressure supply line, a low pressure inlet valve, a high pressure inlet valve; an outlet valve, means for operating said inlet low pressure and outlet valves, and inlet check valves adapted to be opened by the low pressure and closed by the high pressure, and means for opening the high pressure valve when the low pressure reaches a predetermined pressure, means for communicating pressure to the ram and a check valve in the low pressure supply line, whereby low pressure and high pressure are successively applied to said ram. 120

8. In a former, a low pressure supply line, a high pressure supply line, a low pressure inlet valve, a high pressure inlet valve, an outlet valve, means for operating said low pressure inlet and outlet valves, an inlet check valve adapted to be opened by the low pressure and closed by the high pressure and means for opening the high pressure valve when the low pressure reaches a predetermined pressure, a ram, means for communicating pressure to said ram, a check valve in the low pressure supply line, a stationary presser head, a movable presser 125

130

head, and means for charging with a pre-determined load said movable head, and means for supporting the stationary head, so as not to interfere with the charging of the movable head, whereby low pressure and high pressure are successively applied to said ram.

9. In a former, a low pressure supply line, a high pressure supply line, a low pressure inlet valve, a high pressure inlet valve, an outlet valve, means for operating said inlet low pressure and outlet valves, an inlet check valve adapted to be opened by the low pressure and closed by the high pressure and means for opening the high pressure valve when the low pressure reaches a predetermined pressure, a ram, means for communicating pressure to said ram, a check valve in the low pressure supply line, a mov-

able head carried by the ram, having a receptacle mounted thereon below the level of a charging means, a charging means adapted to be reciprocated in and out of charging position consisting of a hopper to carry the charge adapted to be moved over said receptacle on the movable head, between said head and a stationary head of the former, a stationary head, means for support therefor consisting of standards to the rear of the movable head and on either side of said charging apparatus, and means for actuating said charging apparatus at the will of the operator, whereby low pressure and high pressure are successively applied to said ram.

In testimony whereof, I affix my signature.

RUSSELL A. TRACE
